UNITED STATES PATENT OFFICE.

MAX FUSS, OF BERLIN, GERMANY.

ELECTRICAL POTENTIAL-REGULATOR.

1,215,361.

Specification of Letters Patent. Patented Feb. 13, 1917.

Application filed December 3, 1912. Serial No. 734,738.

To all whom it may concern:

Be it known that I, MAX FUSS, a subject of the German Emperor, and resident of Berlin, Germany, have invented certain new and useful Improvements in and Relating to Electrical Potential-Regulators, of which the following is a specification.

The present invention relates to tension regulators for use in connection with electric generators, and is an improvement over my vibratory voltage regulator described in my British Patent No. 7,220 of 1911 and my German Patent No. 253,555. It has for its object to maintain the constancy of the generator voltage under all loads and to generally improve the aforesaid structure.

In the accompanying drawings, like characters of reference indicate like parts in the several views, and:

20 Figure 1 is a general view, partially diagrammatic, showing the entire device as used in connection with a three-phase generator.

25 Figs. 2 and 3 are detail views showing certain levers and adjacent parts in different positions, and

Fig. 4 is a detailed sectional view.

The figures of the accompanying drawing, given by way of example, show the regulator provided with said improvements and in these figures: 1 designates a three-phase generator, 2 is the field winding, 3 the exciting machine with its shunt winding 4 and the shunt resistance 5.

35 The regulator comprises the exciting coil 6 with iron core 7, the tension coil 8 with iron core 9, the contact lever 10 with the movable contact 11 secured thereto by a spring arm 11^a, and finally the stationary contact 12. It comprises besides a rolling lever 13 which is pressed against the bearing support 14 on the one hand by the spring 15, on the other hand by the tractional force of the iron core 7. The spring 15 is provided with an adjusting screw 15'. Positioned approximately in parallel relation to the contact lever 10 is the spring blade 16 which is secured to the lever 17 by means of screws 16^a passing through a block 16^b having a slit 16^c to receive one end of said spring. This block has a fulcrum 16^d interposed between its under side and the upper side of the lever 17 so that the block can be tilted with respect to said lever and the position of the spring end thereby varied, this lever 17 resting on the adjustable bearing

roller fulcrum 18 which can be shifted on the rail 19. This adjustable bearing point is used to regulate the angular relation between the two ends of the spring 16 and consequently to vary its tension. This can best be observed by reference to Fig. 3 wherein it will be noted that, if the lever 10 remains in the position shown, movement of the roller 18 toward the right will raise the right-hand end of the lever 17 and consequently straighten the spring 16.

The intermediate relay 20 comprises two magnet armatures 21 provided with contacts arranged on the armature levers and two fixed counter-contacts 22, as well as a condenser 23. The shunt resistance 5 is mounted in parallel relation to these contacts and the condenser. The resistance 24 is mounted in series with the winding of the intermediate relay 20. 25 is the resistance inserted in series with the tension coil 8 and 26 is a condenser inserted in parallel to 25 and in series with 8.

The operation is as follows:

The tension of the generator is controlled by the tractional force exerted by the tension coil 8 on the iron core 9 and thus moves the contact lever 10 carrying the movable contact 11, so that the latter is alternately brought in and out of contact with the fixed contact 12 by the action of the fluctuating tension of the exciter on the exciter coil 6 and the iron core 7. In this manner the winding of the intermediate relay 20 which is inserted in parallel relation to the contacts 11, 12 is alternately short-circuited and placed in circuit, which in turn produces the short-circuiting and placing into circuit of the shunt resistance 5 through the medium of the relay contacts 21, 22. When the tension rises too high, the iron core 9 lifts the contact lever 10 and the movable contact 11 from the fixed contact 12 whereby, owing to the relay contacts 21, 22 being open, the shunt resistance 5 is inserted in circuit in series with the shunt winding 4 of the exciting machine 3 and is thus maintained until the tension of the generator has approximately reached its normal value whereupon the movable contact 11 again comes into periodical contact with the fixed contact 12. Inversely, when the tension of the generator becomes lower, the contacts 11, 12, owing to the diminution of the tractional force of the tension coil 8, will remain in a closed condition until the tension of the generator has

2
gone up sufficiently to approximately reach the normal value. As the periodical placing in circuit and short-circuiting of the shunt resistance takes place about ten times every second, the adjusting of the tension is effected even when the variations in the load are great, with such a rapidity that no modification of the tension can be noticed.

Now, if the tension is to remain the same for all loads, the ratio between the time the resistance 5 is short-circuited and the time the resistance 5 is in circuit must vary as the load at every given moment. As the tractional force exerted by coil 6 on the iron core 7 increases with the square of the voltage while the antagonistic force of a spring, if directly applied in opposition to such force, increases directly with its elongation, the amplitude of the oscillation of the contact lever 10, produced by the fluctuating exciter voltage, would become the larger, the higher the exciter voltage increases with the load; and as said ratio must vary with the load, there would, with such an arrangement, be a drop of the voltage of the generator with an increase of load. To remedy this defect, the following contrivance has been devised: The iron core 7 of the exciter coil 6 instead of acting directly upon the tractional spring 15, acts thereupon through the medium of a rolling lever 13, the position shown in the drawing corresponding to an average load. The arms of the roller lever 13 which act respectively on the spring 15 and on the iron core 7 are now approximately of equal length. However, if the exciter tension, owing to a greater load, rises, the lever 13 rolls on the support 14 so that the iron core 7 acts upon a shorter and the spring 15 on a longer lever arm whereby a smaller amplitude of oscillation and consequently a longer duration of closing of the contacts 11, 12 and 21, 22 are produced. Inversely, when the load becomes smaller, as well as the tension of the exciting machine, the tractional force of the iron core 7 will become smaller and then the spring 15 will act upon the shorter arm of the roller lever 13 whereby the amplitude of oscillation and with it the time of opening will be increased with reference to the time of closing. By releasing the tension of spring 15 by means of the adjustable screw 15' the roller lever 13 can be adjusted in such a manner that the ratio of the lever arms alters more with the increase of the load than the ratio of the magnetic tractional force to tension of spring. In this case the regulator will adjust to an increase of the tension by rising proportionally to the load; that is to say it will over-compound. This can be taken advantage of for compensating the drop of potential of long lines. This over-compounding of the regulator, to any desired extent corresponding to the nature of the plant,

can be controlled or adjusted during the working of the plant without any oscillation of the tension being produced.

The parts 16 to 19 serve to adjust the tension and can also be employed for increasing the tension with increase of load. As readily seen from the drawing the iron core 9 of the tension coil 8 is suspended by a link 10 from the spring blade 16 which is secured to the lever 17 as described. This lever 17 rests upon the adjustable support or fulcrum 18 which can be moved along the toothed rack 19. The adjusting of the tension of the generator is effected by the tractional force of the tension coil 8 to which the tractional force of the spring blade 16 has to be added. If therefore the contact screw at the fixed contact is screwed upward, the tension of the spring blade 16 is reduced and in order to restore the equilibrium again, the tractional force of 8 must become greater in a corresponding manner i. e. the tension must rise. Inversely, when the screw is adjusted downwardly, the elastic tension of 16 itself is increased and a smaller tractional force of the coil 8 and consequently a smaller tension are necessary for maintaining the equilibrium between the weight of the iron core 9 on one hand and the tractional forces of the coil 8 and the spring blade on the other hand. When the fulcrum or support 18 as shown by the detail figures, drawn at the bottom of the large figure, is shifted toward the left, the lever 17, when the plant is running without a load, is pulled upward and the tension of the spring blade 16 is increased when the iron core 7 of the exciter coil 6 is pulled down by the spring 15. As a consequence, the tractional force is reduced as is also the tension of the tension coil 8 while inversely when the load is increased, the tension of the spring blade 16, as the iron core 7 moves upward owing to the greater tension of the generator, is reduced, so that the tractional force of the tension coil 8 has to increase in order to reestablish the equilibrium which also corresponds to an increase of the tension of the generator. Thus, this device also permits by simply shifting of the fulcrum or support 18 an increase of tension which increases in proportion to the increase of the load. The intermediate relay 20 is constructed in such a manner that the movements of the armature take place as much as possible without any friction and so that effects of inertia are minimized. To this end the armatures of the magnets are mounted so as to be adapted to oscillate around one of the poles of the magnet and are constructed as double armed levers one of the arms of which is acted upon by the magnetic tractional force while the other lever arm is acted upon by the tractional force of a spring. Owing to this arrangement any

lost motion of the armatures of the magnets is avoided.

Finally we have to mention the condenser 26 which is mounted in parallel with the 5 resistance 25 and the tension coil 8.

It is impossible, especially in hydraulic turbines, to avoid alteration of the number of revolutions between the running without any load and the running under full 10 load. But the alteration of the number of periods produces, in spite of a great resistance being inserted in series, an alteration of the tractional force exerted on the iron core, as the self induction of the tension coil 15 is increased when the number of periods is increased. In order to avoid this drawback, the condenser 26 has been provided which receives an amount of current which is the higher the higher the number of periods. By 20 giving the condenser suitable dimensions in proportion to the tension coil, the latter receives an amount of current which is the larger, the higher the number of periods rises so that the tractional force exerted on 25 the iron core and consequently also the adjustment of the tension of the generator remain practically the same for all the numbers of periods.

Having now fully described my said invention, what I claim and desire to secure by Letters Patent, is:

1. In combination, an electrical generator, an exciter therefor having a field winding including a separate resistance, a stationary 35 contact and a movable member having a contact coöperating therewith, electromagnetic means controlled by said contacts and adapted to short circuit said resistance, a solenoid having a core connected to one end 40 of said member and responsive to the electrical condition of said exciter, a second solenoid having a core connected to the other end of said member and responsive to the generator tension, and a curved lever having 45 a bearing surface on which it is adapted to roll, one end being connected to one of said cores and a spring attached to the opposite end acting to oppose the pull of the solenoid on said core.

2. In combination, an electrical generator, an exciter therefor having a field winding including a separate resistance, a stationary contact and a movable member having a contact coöperating therewith, a short 55 circuit around said resistance having contacts under control of said movable member, a solenoid having a core connected to one end of said member and responsive to the electrical condition of said exciter, a second 60 solenoid having a core connected to the other end of said member and responsive to the generator tension, and a curved lever having a bearing surface on which it is adapted to roll, one end being connected to one of 65 said cores and a spring attached to the op-

posite end acting to oppose the pull of the solenoid on said core.

3. In combination, an electrical generator, an exciter therefor having a field winding including a separate resistance, a stationary 70 contact and a movable member having a contact coöperating therewith, means controlled by said contacts and adapted to short circuit said resistance, a solenoid having a core connected to one end of said member and responsive to the electrical condition of said exciter, a second solenoid having a core 75 connected to the other end of said member and responsive to the generator tension, and a yielding blade having connections with 80 said member.

4. In combination, an electrical generator, an exciter therefor having a field winding including a separate resistance, a stationary contact and a movable member having a 85 contact coöperating therewith, means controlled by said contacts and adapted to short circuit said resistance, a solenoid having a core connected to one end of said member and responsive to the electrical condition of said exciter, a second solenoid having a core 90 connected to the other end of said member and responsive to the generator tension, and a yielding blade having connections with 95 said member and provided with an adjustable support.

5. In combination, an electrical generator, an exciter therefor having a field winding including a separate resistance, a stationary 100 contact and a movable member having a contact coöperating therewith, means controlled by said contacts and adapted to short circuit said resistance, a solenoid having a core connected to one end of said member and responsive to the electrical condition of said exciter, a second solenoid having a core 105 connected to the other end of said member and responsive to the generator tension, a yielding blade having connections with said member and provided with an 110 adjustable support, and a spring resisted roller member connected to one of said cores to oppose the pull of its solenoid.

6. In combination, an electrical generator, an exciter therefor having a field winding 115 including a separate resistance, a stationary contact and a yieldingly supported movable member having a contact coöperating therewith, a short circuit around said resistance having contacts under the control of said movable member, electro-magnetic means responsive to fluctuations of current in said exciter for vibrating one end of said member, and a solenoid in series relation with an impedance and capacity in parallel and 120 adapted to be energized by the generator tension for controlling the movements of the opposite end of said member.

7. An electrical regulator comprising co-operating contacts, a movable member ac- 125

tuating one of said contacts, means comprising a winding for actuating said member, means providing a fulcrum for said member, another winding for actuating said fulcrum-providing-means, a tension element, and a lever having a rolling bearing surface for varying the action of said tension element in opposition to the tractive force of one of said windings.

10. 8. An electrical regulator comprising co-operating contacts, a movable member actuating one of said contacts, means comprising a winding for actuating said member, means providing a fulcrum for said member, another winding for actuating said fulcrum-providing-means, a tension element, a lever having a rolling bearing surface for varying the action of said tension element in opposition to the tractive force of one 15 of said windings, and means for varying the tension of said tension element.

9. An electrical regulator comprising a stationary contact, a movable contact, a movable member actuating said movable contact, means comprising a winding for actuating said member, means providing a fulcrum for said member, another winding for actuating said fulcrum-providing-means, a tension element adapted to act in co-operation 25 with one of said windings, and a lever subject to the action of the companion winding for influencing the tension of the element.

10. An electrical regulator comprising a stationary contact, a movable contact, a movable member actuating said movable contact, means comprising a winding for actuating said member, means providing a fulcrum for said member, another winding for actuating 35 said fulcrum-providing-means, a tension element adapted to act in co-operation with one of said windings, a lever subject to the action of the companion winding for influencing the tension of said element, 40 and an adjustable fulcrum for said lever.

11. An electrical regulator comprising a stationary contact, a movable contact, a mov-

able member actuating said movable contact, means comprising a winding for actuating said member, means providing a fulcrum for 50 said member, and another winding for actuating said fulcrum-providing-means, one of said windings being in series relation with an impedance and capacity in parallel for influencing the movements of one end of 55 said member.

12. An electrical regulator comprising a stationary contact, a movable contact, a movable member actuating said movable contact, a pair of solenoids having cores connected to 60 opposite ends of said member, a resilient blade having connection with one end of said member, and a lever supporting the opposite end of said blade and having jointed connection with the opposite end of said 65 member.

13. An electrical regulator comprising a stationary contact, a movable contact, a movable member actuating said movable contact, a pair of solenoids having cores connected to 70 opposite ends of said member, a resilient blade having connection with one end of said member, and a lever having an adjustable fulcrum and supporting the opposite 75 end of said blade and having jointed connection with the opposite end of said member.

14. An electrical regulator comprising co-operating contacts, a movable member actuating one of said contacts, means comprising a winding for actuating said member, means 80 providing a fulcrum for said member, another winding for actuating said fulcrum-providing means, a tension element controlling the action of one of said windings, and a variable-leverage-device for varying the 85 controlling action of said tension element on said winding as one of said windings varies in strength.

In testimony whereof I have hereunto set my hand in presence of two witnesses.

MAX FUSS.
